UNITED STATES PATENT OFFICE.

ARVID LINDSTRÖM, OF WÄSTERÅS, SWEDEN.

INSULATING AND COOLING MEANS FOR TRANSFORMERS.

1,334,041.

Specification of Letters Patent. Patented Mar. 16, 1920.

Application filed March 6, 1919. Serial No. 281,088.

To all whom it may concern:

Be it known that I, ARVID LINDSTRÖM, subject of the King of Sweden, residing at Almelund 3, Wästerås, Sweden, have invented certain new and useful Improvements in Insulating and Cooling Means for Transformers, of which the following is a specification.

It is known that the dielectric strength of gases increases with the pressure of the gas. For air, carbonic acid, nitrogen and others it has been found, that exact, or nearly exact proportionality prevails between the strength (break-down voltage) and the pressure within wide limits. It has therefore been proposed to employ compressed gas as insulating medium in transformers instead of oil or air of atmospheric pressure. As far as known, it has only come to suggestions in this direction, probably depending upon the fact that gases, at atmospheric pressure as well as in a compressed state, are bad conductors of heat, nor are they able to carry off the heat by so-called convection in such degree as for instance oil. The employment of the latter in transformers is based not only upon its insulating but also, and not least, upon its heat-conducting properties. If a compressed gas were employed instead of oil under equal conditions in other respects, the temperature of the active parts of the transformer (winding and core) would be correspondingly higher.

The object of the present invention is to provide a transformer having a compressed gas as insulating and cooling medium, in which a considerable difference of temperature can be allowed between the active parts and the cooling medium, without surpassing the allowable absolute temperature of the former parts. This is accomplished by keeping the compressed gas and the inside of the casing at so low temperature, that the winding, in spite of a high difference of temperature with respect to the gas, can be moderately warm or even cold.

In the accompanying drawings, I have shown means for carrying out my invention, which have been found to be very efficient for the purpose.

In these drawings:—

Figure 1 is a side elevation, partly in section, of one form, and

Fig. 2 is a similar view of a slightly different form.

In Fig. 1 *a* is the inlet to the coil *b*. *c* is a high pressure compressor from which leads the pipe *d* to the coil *b*. *e* is a pipe from the coil *b* to the expansion nozzles *f* and *g*. This pipe *e* is provided with a valve *h*. *i* are terminals for suitable connections on the casing *j*. *k* is the low tension winding, and *l* the high tension winding. *m* is insulation. *n* is the low pressure pipe connecting the compressor *c* with the casing *j*.

In Fig. 2 the casing *j'* contains the tubular cooling coil *o*.

For cooling the gas many different ways may be employed, only a couple of which may be mentioned here.

(1) The gas is compressed with removal of heat to a high pressure and rather low temperature (which may be so low that the gas is liquefied). From this state, the gas is allowed to expand in entering the transformer casing to the pressure prevailing therein which is from five to ten atmospheres so that the temperature of the gas is considerably lowered during the expansion. As the gas is heated by absorbing the loss heat of the transformer, it is removed therefrom to be compressed and cooled again, and so on. The gas thus is brought to circulate continuously with a speed depending upon the load of the transformer and on the temperature allowed for its winding and other parts.

(2) The gas is permanently inclosed within the transformer under a certain pressure which may be maintained by means of a compressor or the like. The gas and the inside of the casing are cooled by means of pipes traversed by a cooling medium, gaseous or liquid in about the same manner as that employed in ordinary cooling plants.

If in any of these or in another manner the temperature of the gas is kept very low, a further increase of the dielectric strength of the gas is gained, as the latter is shown by experience to be substantially inversely proportional to its absolute temperature. If the gas and the interior of the casing are kept at so low temperature that the temperature of the winding also will be quite or comparatively low the advantage is gained that the specific resistance of the winding will be correspondingly low and thus either the ohmic losses or the necessary winding area and copper quantity small.

On the other hand, such a low temperature is unsuitable for the iron core of the transformer, as the eddy current losses therein will be the greater, the lower the resistivity 5 and the temperature of the iron are. It is therefore preferred to provide a heat insulation for the iron core so as to make its temperature higher than that of the winding. By a special arrangement it can be put 10 in direct heat conducting communication with the surrounding air so as to yield a greater or smaller portion of its heat directly thereto, so that the said portion will not contribute to the heating of the compressed gas and the winding. 15

Having now described my invention and the manner of its operation, I declare that what I claim is:—

1. In transformers, the combination of a 20 casing filled with an insulating gas at a pressure superior to the atmospheric one, a compressor for maintaining said pressure and a device for producing low temperature in the transformer casing by gas expansion.
2. In transformers, the combination of a 25 casing capable of sustaining a pressure superior to the atmospheric one, a compressor

for compressing a gas to a very high pressure, a cooling device for said compressed gas, and an expansion device between the 30 cooling device and the transformer casing.

3. In transformers, the combination of an iron core, a winding, a casing inclosing both, means for circulating a gas at a high pressure and low temperature through said casing and around said winding, and an insulating layer surrounding said iron core so as to protect it against the cooling action of 35 said gas.

4. In transformers, the combination of an 40 iron core, a winding, a casing inclosing both and in heat-conducting contact with said iron core, means for circulating a gas at high pressure and low temperature through said 45 casing and around said winding, and an insulating layer surrounding said iron core on the sides not in contact with the casing.

In testimony whereof I have affixed my signature in the presence of two witnesses.

ARVID LINDSTRÖM.
